UNITED STATES PATENT OFFICE.

CHARLES D. VEZEY, OF BERKELEY, AND CLAUDE MARINER, OF OAKLAND, CALIFORNIA.

KILN.

1,362,063.

Specification of Letters Patent. Patented Dec. 14, 1920.

Application filed January 13, 1919. Serial No. 270,966.

To all whom it may concern:

Be it known that we, CHARLES D. VEZEY and CLAUDE MARINER, citizens of the United States, residing at Berkeley and Oakland, respectively, in the county of Alameda and State of California, have invented certain new and useful Improvements in Kilns, of which the following is a specification.

This invention relates to furnaces of the type wherein the fire acts upon material fed thereto for the purpose of roasting, calcining, drying or burning such material.

The principal object of the invention is to provide a furnace or kiln of this character in which the material acted upon moves continuously through the roasting chamber. Another object is to provide a construction by which one or more kilns may be connected to a single source of draft, and in which the draft through each furnace is in the opposite direction to the direction of movement of the material passing therethrough.

A further object is to arrange the chamber into which the material is fed with an inclined surface so that the material will slide of itself toward the exit opening and in which the hottest flame will meet the material which has been longest in the furnace.

Still further objects are to arrange convenient means for having the material acted upon for a shorter or longer interval depending on the length of furnace through which the heated gases pass, and to provide a return down draft flue which will heat the bottom of the pile of material on the floor of the roasting chamber itself.

With these and other objects in view, the invention consists of certain novel features of construction, combinations and arrangements of parts hereinafter described and more specifically pointed out in the appended claims; it being understood that changes in form, proportion, size and minor details of construction within the scope of the claims may be resorted to without departing from the spirit of the invention or sacrificing any of the advantages thereof.

Referring to the drawings forming a part of this specification:

Figure 1 is a view in plan of the improved furnace or kiln.

Fig. 2 is a view in longitudinal section

through the combustion and roasting chambers.

Fig. 3 is a view in section through the draft flue showing the suction fan.

Fig. 4 is an enlarged horizontal section through the combustion chamber and lower end of the roasting chamber.

Fig. 5 is an enlarged cross section through the roasting chamber.

Referring to corresponding parts in the several views by the same numerals of reference, our invention comprises a combustion chamber 1 having the front and rear walls 2 and 3, the side walls 4 and arched roof 5. The front wall is provided with doors 6, and we have here illustrated it as being heated with oil burners 7. Within the combustion chamber is a transverse bridge wall 8, and in the rear wall are two or more openings 9 through which the heated gases pass into the roasting chamber 25.

The side walls and arch of the combustion chamber are continued on the rear of wall 3 for a short distance and are then inclined upwardly at a rather sharp angle. In the floor of this rearward continuation is an opening 10 across which are set grate bars 11.

The inclined roasting chamber above mentioned comprises a floor 12, side walls 13 and arched roof 14. The side walls are continued below the floor 12 forming below the latter a return flue 15. These walls rest on footings 16 in which are built the ends of vertical bars 17 which rest against the outside of the side walls and are tied together above the latter by means of rods 18 thus taking care of the thrust produced by the arched roof.

The return flue is also provided with a floor 19 from which rises parallel walls 20. The latter extend the entire length under floor 12 and may be constructed of brick laid in checkered style so as to provide communication between the adjacent passageways.

At the upper end of the roasting chamber the floor 12 is stopped short of the end wall 26, thus providing communication between the roasting chamber and the return flue. This passageway may be closed by means of the pivotally mounted damper plate 27. At this end of the roasting chamber there is also provided a filling opening 28, and with-

in the chamber back of this opening is a wall 30 built of brick work having checkered openings. This wall prevents the material which is entered through opening 28 from falling through the passage 29 into the return flue.

The roof 14 is at suitable intervals provided with holes 32 having tight fitting cover plates, these holes giving access to the 10 interior of the chamber for inspection and to start the material sliding in case it should get stuck. In the side walls are provided openings 33 extending transversely through the walls and which are closed on the outer 15 side by tight fitting doors 34. Between the inner and outer layers of the brick work forming the walls 13 are formed vertical passageways 35 which extend in opposite direction from the top and bottom of the 20 opening 33. Above this opening the brick work between the passageway 35 and the chamber 25 is set in checkered style so as to provide communication therebetween. Below the opening 33 the passageway is provided 25 with a transverse portion 37 which communicates with the return flue. A damper plate 38 is pivotally mounted on one side of the passageway 35 and has an operating rod 39 which extends outside of the wall 30 13. This damper is positioned below the horizontal passageway 33 at such a distance that when in its open position the upper end will be below the floor of the passageway. The sides of opening 33 next to the roasting 35 chamber are slightly divergent away from the said chamber as shown at 51 and this diverging opening is adapted to be closed by a plate of refractory material 52. To hold the same in place we provide a brick 54 40 which is set on edge across passageway 35, has its inner end abutting against the back of plate 52 and its outer end held in position by the door 34. The plate 52 and abutment 54 just described are provided with 45 slotted openings 55 that when they are hot they can be lifted by inserting the end of a poker or slash bar through these openings.

Extending transversely under the furnace above described is a draft flue 40 to which 50 is attached the suction intake 41 of a fan 41. The outlet of the latter is connected to a stack 42. Communication is made between the return flue and the draft flue by means of the short vertical flue 43. This flue is 55 the width of the furnace and communicates with the draft flue through a hole 44 which may be closed by a vertically movable damper 45. In the upper part of flue 43 are formed arched walls 46 which are spaced the same 60 as walls 20 and against which the lower ends of the latter rest.

The slant of the floor 12 is continued down through the grate bars and below the floor of the combustion chamber is provided with 65 a chute 47 having a close fitting closure 48.

One of the side walls back of the combustion chamber has a large door 50 which may be used either as a clean-out door or to remove the material which has been roasted on the inclined floor of the chamber 25. It will be noted that we have shown the combustion chamber set on an arch which will permit a vehicle to move under the chute 47.

In use the material to be burned is dumped 75 into the roasting chamber through the opening 28 and slides down the floor thereof. In the meantime the fan draws the flame and heated gas from the combustion chamber into the roasting chamber and up the full 80 length of the latter. Ordinarily the draft then passes through the openings in wall 30 around the end of the floor 12 into the return flue.

The gases still retain a large amount of 85 heat which is transmitted through the thin floor 12 to the material lying directly thereon. The gases then pass down through the passageways below floor 12 into the short vertical flue 43 and so to the draft flue 40 and the fan 41.

The material operated upon is calcined or burned by the intense heat from the combustion chamber and as it reaches a certain degree of friability is pushed down by the weight of the superimposed mass of fresh 95 material which is deposited through opening 28. If it is a material which is burned the ashes fall through the grate bars and are periodically removed through the chute. If it is a material which is roasted and remains 100 in large lumps it may be removed either through door 50 or no grate bars may be used and so the material falls directly into the chute.

If the mass of material becomes stuck in 105 the roasting chamber it may be loosened by inserting a suitable bar through the openings in the side or top of the chamber. In case it is desired to have the material acted upon for a shorter interval then the damper 110 27 is closed and one or more of the dampers 38 opened. This allows the gases to pass through the checkered openings in the chamber lining down the corresponding by pass flue 35 into the return flue 15. This in 115 effect by-passes the draft at a point part way up the roasting chamber and for some purposes increases the efficiency of the furnace.

The upper end of the inclined chamber is 120 constructed with a flat upper roof as shown at 60 thus forming an enlarged compartment where the material is dumped into the said chamber. The opening 28 is in this flat roof and in practice the latter may form 125 a part of a roadway over which the material is carried and dumped directly into the opening.

Our invention gives a kiln suitable for 130 burning limestone, calcining magnesite,

roasting the various ores and burning refuse such as garbage.

Having thus described our invention we claim as new and wish to cover by Letters 5 Patent:

1. A kiln of the character described comprising side walls, a roof and a floor forming an upwardly inclined roasting chamber and a parallel adjoined downwardly inclined return flue connected to said chamber at their upper ends, a draft flue connected to the lower end of said return flue, a damper for closing the connection between said chamber and said flue, and said walls 10 having passageways connecting said chamber and said flue and means for closing said passageways.

2. A kiln comprising side walls, a roof and a floor supported above the bottom of 20 said side walls, said walls, roof and floor forming an upwardly inclined roasting chamber and a parallel downwardly inclined return flue communicating at their upper ends, said side walls having by pass 25 flues connecting said roasting chamber with said return flue and dampers for closing said by pass flues.

3. A kiln comprising side walls, a roof and a floor inclined in an upward direction 30 forming a roasting chamber and a return flue, said kiln having an opening connecting said chamber and said flue at the upper end thereof, a damper for regulating said opening, said walls having passageways intermediate the ends of said chamber extending 35 between the latter and said flue, a damper for closing said passageways, a firebox communicating with the lower end of said

chamber and a draft flue communicating with the lower end of said return flue. 40

4. A kiln of the character described comprising an upwardly inclined portion comprising a bottom, side walls and a roof, a floor extending between said side walls forming a chamber and a parallel return flue, a 45 plurality of longitudinal parallel spaced walls extending between said bottom and said floor, said inclined portion having passageways between said chamber and said flue, means for closing said passageways, a horizontal fire-box communicating with the lower end of said inclined portion, a draft flue extending transversely below said kiln, and a communicating flue extending therefrom to said return flue. 50

5. A kiln of the character described comprising an upwardly inclined portion formed of a bottom, side walls and a roof, a horizontal continuation at the foot of said inclined portion forming a fire-box, a division floor extending between said side walls forming a roasting chamber above and a return flue below said floor and having a communicating passage at their upper ends, a damper for closing said passage, said side 60 walls having transverse openings into said chamber, means for closing said openings at the ends thereof, said walls having vertical passageways which cross said openings and dampers in said passageways below said 65 transverse openings. 70

In testimony whereof we affix our signatures.

CHARLES D. VEZNEY.
CLAUDE MARINER.
